US00D565585S

(12) **United States Design Patent** (10) **Patent No.:** **US D565,585 S**
(45) **Date of Patent:** **** Apr. 1, 2008**

(54) **USER INTERFACE FOR A PORTION OF A DISPLAY SCREEN**

(75) Inventors: **Steven Ryan Gunn**, Seattle, WA (US); **Gregory Allen Martinez**, Seattle, WA (US); **Vadim Gorokhovsky**, Redmond, WA (US); **Christian Robert Lehew**, Redmond, WA (US)

(73) Assignee: **Microsoft Corporation**, Redmond, WA (US)

(**) Term: **14 Years**

(21) Appl. No.: **29/276,155**

(22) Filed: **Jan. 17, 2007**

(51) LOC (8) Cl. **14-04**

(52) U.S. Cl. **D14/487**

(58) Field of Classification Search D14/485-495; 715/700-867, 973-977

See application file for complete search history.

(57) **CLAIM**

The ornamental design for a user interface for a portion of a display screen, as shown and described.

DESCRIPTION

The FIGURE is a front view of a user interface for a portion of a display screen showing our new design.

The broken lines shown in the drawings are included for the purpose of illustrating portions of the user interface that form no part of the claimed design. The broken line showing of the display screen forms no part of the claimed design.
